R. C. PORRAS

GRATED WINDOW

Filed Feb. 2, 1925

Fig. 1.

UNITED STATES PATENT OFFICE.

RUBÉN CASTRO PORRAS, OF SAN JOSE, COSTA RICA.

GRATED WINDOW.

Application filed February 2, 1925, Serial No. 6,313, and in Costa Rica September 4, 1924.

This invention relates to grated windows and more especially to windows having sliding sashes to which may be secured bars. The object of the invention is to supply the opening of the window, when the lower sash is raised or the upper sash is lowered, with bars to prevent the entrance of would-be intruders.

A further object of the invention is the release and discarding of the bars when they are found unnecessary. This is accomplished by mounting all of the bars on a horizontal strip or rod that is adapted to be locked or otherwise secured to the bottom rail of the lower sash and the top rail of the upper sash and may be released by means of a key, or immediately attached again.

These and other details and objects of the invention are more fully described in the following specification, set forth in the appended claims and illustrated in the accompanying drawings, wherein:

Figure 1 is a perspective view of a window from the interior with the two sashes partly opened and the openings filled with the grating.

Fig. 2 is a face view of the inside of the window with the upper sash closed and the lower grating released.

Fig. 3 is a detail sectional view showing the operation of the lock.

Fig. 4 is a cross sectional view of Fig. 3.

Fig. 5 is a detail perspective view of a part of the grating.

As best shown in Fig. 2 the window may present the appearance of an ordinary frame and sashes when it is desired to dispense with the grating and protecting means which although not in sight may be made immediately available.

In Fig. 1 the sashes 5 and 6, being respectively the upper and lower sliding members of the window, are provided with gratings 5 that comprise the metallic strip or rod 7 and the bars 8 located at a right angle to each other, the ends of the bars entering perforations in the rods and being welded or swaged together, both the gratings being identical 0 but the position of the bars and rods are reversed, one being on the top of the sash 5

and the other being locked to the bottom of sash 6.

The walls of the building above and below the window frame are provided with suitable recesses below the sill and above the head of said frame and into which the bars 8 run when the windows are closed while the rods 7 have suitable recesses into which they rest when the sashes are closed, one of these recesses 9 being shown in Figs. 3 and 4 in the window sill 10.

The rods 7 are secured to the sashes by means of the locks 11, shown more clearly in Fig. 3 as being a type commonly used in disks and having the laterally operating bolts 12, with a guard 13, that enter the slot 14 of the rod 7 and spring outward and prevent retraction of the lock until a key is inside. Both of the sashes have key holes 15 to afford a means for the operation of the lock.

By this means the lower grating may be left on the sill 10 and the bars in their recesses as shown in dotted lines in Fig. 2.

The upper grating may also be released and retained in its elevated position by means of an eye 16 that enters a recess in the window frame and a pin 17 may be passed through the frame and eye when the grating is unlocked and released and the upper sash may be lowered, leaving an unobstructed opening above it.

It is obvious that equivalent means may be adopted to hold the upper grating in its elevated position when released from its sash and that other means than the lock shown may be resorted to, also other arrangements and modifications may be used without departing from the essential features above described or from the scope of the appended claims.

What I claim as new is:

1. In grated windows, the combination of window sashes having locks at their closing edges, a window frame having recesses above the upper sash and below the lower sash, and rods carrying vertical bars and adapted to fit in the recesses and having each a slot into which the bolts of the locks may enter and engage said rods.
2. In grated windows, the combination of

a window frame having recesses at its top and bottom, an upper sash below the top recess, a lower sash above the lower recess, rods having vertical bars and adapted to lie in the recesses and having each a slot, locks on the sashes and adapted to enter the slots so that their bolts will engage the bars, and

an eye on the upper rod with a pin to hold it in the upper recess when the lock is disengaged.

In testimony whereof I hereunto affix my signature.

RUBÈN CASTRO PORRAS.
